United States Patent Office

Des. 211,951
Patented Aug. 13, 1968

211,951

TELEPHONE HEADSET

George Thomson, London, Ontario, and William J. Driver,
Burlington, Ontario, Canada, assignors to Northern
Electric Company, Limited, Montreal, Quebec, Canada

Filed Sept. 26, 1967, Ser. No. 8,733

Term of patent 14 years

(Cl. D26—14)

FIG. 1

FIG. 2

FIG. 3

FIG. 1 is a perspective view of a telephone headset, showing our new design;

FIG. 2 is a top perspective view of the telephone headset; and

FIG. 3 is a side perspective view opposite FIG. 1.

We claim:

The ornamental design for a telephone headset, as shown and described.
